UNITED STATES PATENT OFFICE.

OSCAR L. NEWSOM, OF FITZGERALD, GEORGIA.

TRACK-TOOL.

1,365,265.

Specification of Letters Patent. Patented Jan. 11, 1921.

Application filed April 3, 1920. Serial No. 371,010.

To all whom it may concern:

Be it known that I, OSCAR L. NEWSOM, a citizen of the United States, residing at Fitzgerald, in the county of Ben Hill, State 5 of Georgia, have invented certain new and useful Improvements in Track-Tools; and I do hereby declare the following to be a full, clear, and exact description of the invention, such as will enable others skilled in the art 10 to which it appertains to make and use the same.

This invention relates to new and useful improvements in railway tools.

One object of the present invention is to 15 provide a novel and improved tool with which bent splice bars, fishplates, friction plates, rails, and the like can be easily and quickly straightened.

Another object is to provide a tool of this 20 character which is strong and durable, and which is simple in construction and easy to operate.

Other objects and advantages will be apparent from the following description when 25 taken in connection with the accompanying drawing.

In the drawing:

Figure 1 is a side elevation of the tool in operative relation to a railway rail and the 30 plate being straightened.

Fig. 2 is a top plan view of the same.

Fig. 3 is an enlarged vertical sectional view taken on the line 3—3 of Fig. 1, through the foot block, showing the means for detachably securing the same to the lever of the tool.

Referring particularly to the accompanying drawing, 10 represents a portion of a railway rail, 11 the ties, and 12 the bent plate 40 to be straightened by the tool.

The tool comprises a long and tapering lever having ratchet teeth 14, on its upper edge midway of its length, the lever being represented by the numeral 13. The wider 45 end of the lever is formed with an apertured lug 15, on its upper portion to which pivotally connected the L-shaped jaw 16. This jaw coöperates with the fixed jaw 17 carried by the lower portion of the wider end of 50 the lever. Extending vertically from the jaw 16 is a post 18 to which is pivotally con-

nected one end of the pawl 19, the other end of said pawl having a nose 20 which engages with the ratchet teeth 14, before-mentioned. Secured on opposite sides of the lever, adjacent the teeth 14, are the vertical standards 21, between the upper ends of which is pivotally mounted the pawl 22, whose nose engages with ratchet teeth 23 formed on the upper edge of the pawl 19. Secured to the 60 lower edge of the lever, at a point between the fixed jaw 17 and the standards 21, is a foot block 24 which is adapted to be brought to bear on the bent plate to be straightened, as clearly seen in the drawing, while the 65 jaws 16 and 17 grip the tread portion of the rail 10. It will be noted that the plate to be straightened is placed across the ends of the ties, outwardly of the rail.

The pawls serve to hold the jaws in firm 70 engagement with the railway rail while force is applied downwardly on the smaller end of the lever. The foot block is thus forced against the convex portion of the bend of the plate and said bend pressed down and 75 the plate properly straightened.

The foot block has a dowel pin 25 which engages in an opening 26 in the lower edge of the lever, whereby the block can be removed when not needed.

What is claimed is:

A bending and straightening tool comprising a power lever having teeth on its upper edge face, a fixed jaw on one end of the lever, a movable jaw carried by the end of 85 the lever for coöperation with the fixed jaw to grip a portion of a railway rail, a pawl connected with and movable by the movable jaw and engaging the teeth of the lever, said pawl being provided with teeth, a pawl supported on the lever over the first pawl and engaging the teeth of said first pawl, and a removable foot block carried by the lower edge portion of the lever for bending engagement with a piece of work to be 90 straightened.

In testimony whereof I affix my signature in the presence of two witnesses.

OSCAR L. NEWSOM.
